(57) **CLAIM**

We claim the ornamental design for the gas valve, as shown and described.

DESCRIPTION

FIG. 1 is a top, front, and right perspective view of a gas valve showing our new design;

FIG. 2 is a top, front, and left perspective view thereof;

FIG. 3 is front, bottom right perspective view thereof;

FIG. 4 is back, bottom, left perspective view thereof;

FIG. 5 is a front elevation view thereof;

FIG. 6 is a back elevation view thereof;

FIG. 7 is a right side elevation view thereof;

FIG. 8 is a left side elevation view thereof;

FIG. 9 is a top plan view thereof; and,

FIG. 10 is a bottom plan view thereof.

The broken lines shown in the figures are for the purpose of illustrating portions of the gas valve which form no part of the claimed design.
